UNITED STATES PATENT OFFICE.

ALBERT J. MEIER, OF GLENDALE, MISSOURI.

HEADING-MACHINE FOR STEEL PACKAGES.

1,025,637.

Specification of Letters Patent.

Patented May 7, 1912.

Application filed June 5, 1911. Serial No. 631,285.

To all whom it may concern:

Be it known that I, ALBERT J. MEIER, a citizen of the United States, residing at Glendale, in the county of St. Louis and State of Missouri, have invented certain new and useful Improvements in Heading-Machines for Steel Packages, of which the following is a specification.

This invention relates to certain new and useful improvements in heading machines for steel packages.

The object of the invention is to provide an improved machine of this type which will effectively and automatically secure the steel cover of a steel package in position on the latter.

In the drawings: Figure 1 is a rear elevation of a machine constructed in accordance with the present invention, Fig. 2 is an end elevation, Fig. 3 is a bottom plan view of the heading device, Fig. 4 is a side elevation of the heading device, parts being broken away and shown in section, Fig. 5 is a top plan view of the preferred form of heading device, and Fig. 6 is a section taken on the line 6—6 of Fig. 5.

The machine includes a table 1, which rests on a bed plate 2, the latter being supported by suitable legs or standards 3. A pair of uprights 4 are rigidly secured to the ends of bed plate 2, and are provided with guide-ways 5, in which slides the vertically reciprocating die-holder 6. The upper ends of the uprights 4, are equipped with journal boxes 7 in which is journaled a crank shaft 8, the latter being driven by a band-wheel 9, which receives its power from a belt (not shown), the band-wheel being loosely mounted on an end of the crank shaft 8. A pitman 10 is loosely mounted on crank shaft 8 and at its lower end is formed with a threaded socket in which is adjustably mounted a threaded stem 11, formed with a spherical head 12, the latter being received in a socket 13 provided therefor in the upper end of the die holder 6, and being held in socket 13 by a plate 14, the latter being bolted to the die holder 6 and having an aperture through which stem 12 passes. Obviously by proper adjustment of the threaded stem 11, the extent of movement or throw of the die holder can be governed

to effect the desired or necessary action of the die holder 6.

A semi-circular rib 15 on the table 1 centers the steel package in proper position beneath the heading device. The heading device, which is illustrated in detail in Figs. 3 and 4, includes an upper disk 17, formed with a stem 18, the latter being received in a socket provided therefor in the die holder 6, and being rigidly secured to the latter in any suitable manner, so as to partake of the movements thereof. A lower disk 19 is suspended from the upper disk 17 by means of bolts 20 or their equivalent, so that the lower disk 19 is capable of moving up and down on the said bolts 20, and, in order to permit of the stated movement of the lower disk 19, the bolt heads 21 are received in enlarged openings 22 formed in the under face of lower disk 19 of sufficient size to allow of free movement of the bolt heads 21 therein.

The disk 17 is formed with a series of pockets 23, and the disk 19 is formed with a series of similar pockets 24, which latter are, however, very shallow, coil springs 25 being received in the oppositely disposed pockets 23 and 24 and serving to hold the disks normally in separated relation.

The lower disk 19 is provided with a series of pairs of ears 26, the pairs being arranged in spaced relation and the ears of each pair being spaced apart to receive the fingers 27 in said space, pins 28 being employed which pass through the ears 26 and through the fingers 27 and serve to pivotally relate said fingers to said ears. The fingers 27 are somewhat L-shape, their vertical portions at the upper ends thereof having rounded projections 29 and the horizontal portions at their free ends being formed with concave faces 30 and with rounded noses 31, which latter merge into the concave faces 30, as clearly depicted in Fig. 4 of the drawings.

The rounded projection 29 of each pivoted finger 27 is engaged by a cam or wedge-shaped plate 32, which is secured to the periphery of the upper disk 17 by means of screws 33, the plates 32 being received in cut-out portions 34, provided therefor in the periphery of the upper disk 17, the up-

per ends of the plates 32 abutting the shoulders 35 formed by the cut-out portions 34 and by virtue of such engagement hold the plates 32 rigidly against movement, relieving the screws 33, which have their heads countersunk, of any strain during the time said plates 32 are in action.

In Fig. 4 of the drawings a steel casing 36, is shown in fragment, which has its top edge 10 rolled over a wire ring, inclosing the latter, and a steel cover 37 has a sunken central portion which fits on the interior of casing 36, and a rim which conformably engages over the rolled edge of casing 36, the rim 15 being formed with a series of lips 38. The lips 38 are formed on the rim of the cover prior to the latter being placed in position on the casing.

The lower disk 19 has its lower end 20 formed with a peripheral concave groove 39, which conformably receives and fits over the inner upper side of the rim of the cover 37, as clearly depicted in Fig. 4, the function of the disk 19 being that of holding the 25 cover firmly in place during the bending of the lips 38. The upper disk 17 is formed with a downwardly extending annular guide member 40 which is slidingly received in an opening 41, provided therefor in the lower 30 disk 19.

In operation the casing 36 is placed on table 1 in engagement with rib 15, the cover being placed on the casing 36 and so positioned with respect to the fingers 27, that the 35 latter will be in register with the respective lips of the cover, it being understood that there are as many fingers 27 as there are lips on the rim of the cover. The heading device is then lowered, the lower disk 19 engaging 40 the cover of the package and the rim of the cover enters the annular groove 39 of said lower disk before the die holder 6 reaches the limit of its downward stroke. After the lower disk 19 engages the cover, 45 in a manner depicted in Fig. 4, the cover prevents same from further downward movement, with the result that the upper disk 17 continues to move downwardly and thereby compresses the springs 25, which 50 springs in turn exert pressure on the lower disk and the latter being in engagement with the cover holds same firmly in place on the casing. At the same time the wedge-shaped or cam-faced plates 32 borne by the upper 55 disk 17 engage the rounded projection 29 of the fingers 27 that are pivoted to the lower disk 19, moving the vertical portions of the fingers outwardly and effecting corresponding inward and also upward movement 60 of the horizontal portions of the fingers, whereby the rounded noses 31 of the fingers bend the lips 38 of the cover rim over the rolled upper edge of the casing 36, as clearly illustrated in Fig. 4. On the 65 idle or upward stroke of the die holder and

the heading device borne thereby, the springs 25 are permitted to expand, which effects movement of the disks 17 and 19 to their relative extremes of movement, and consequently causes the wedge-shaped plates 32 to move away from the projection 29 of the fingers 27, permitting the horizontal portions of the latter to move past the lips 38 which have been bent thereby into locked position.

In Figs. 5 and 6 of the drawings the preferred form of the heading device is illustrated, which is especially adapted to secure or lock the cover on the casing, in a manner disclosed in my co-pending application filed June 5, 1911, Serial No. 631,287. In the said Figs. 5 and 6, the upper disk 17' has a depending guide member 40' which is slidingly received in an opening 41', provided therefor in the lower disk 19', the upper disk having a stem 18' for securement to the die holder, as described above in connection with the preferred form of the invention. Screws 20' are secured to the upper disk 17' and have their heads 21' received in enlarged openings 22' formed in disk 19'. Fingers 27' are pivoted to rods 28' which latter are received in openings provided therefor and which extend through the periphery of the lower disk 19' as shown in dotted lines in Fig. 5, the rods being held in place by means of screws 42 whose ends are pointed and received in depressions provided therefor in the rods 28', for the purpose of preventing longitudinal movement 9 of the rods 28'.

Each finger has a rounded nose 31' at its lower end and a rounded projection 29' at its upper end. Springs 25' are interposed between the disks 17' and 19' and act in a manner precisely as described in connection with the other form of the invention. The upper disk 17' is formed with a series of openings 43, the outer walls of which are inclined and receive the wedge or cam-faced plates 32', secured by means of screws 33'. Small coil springs 44 are received in pockets provided therefor in the lower disk 19' and exert pressure against the rear faces of the fingers 27', and move the upper ends of the latter outwardly in engagement with the plates 32'. The lower disk 19' is also formed with openings 45 in which the lower ends of the fingers are pivoted. The disk 19' is formed with an inner circumferential concave groove 39' which receives the rim 38' of the steel cover, said rim being of inverted U-shape in cross-section and being annealed so that the rounded noses of the pivoted fingers will force or press the inner side portions of the rim outwardly, thereby forming indentations which latter engage under the rounded reinforced upper edges of the casing 36' of the steel package, as depicted to the left of Fig. 6, as distinguished

from the right of said Fig. 6, which shows the rim between the indentations.

- In operation the cover is placed on the casing, and the latter is properly positioned 5 on the table 1, and on the working or down stroke of the heading device the lower disk 19' engages the cover, the rim of the latter entering the groove 39' before the die holder 6 reaches the limit of its downward stroke. 10 After the lower disk 19' engages the cover, the latter prevents same from further downward movement, with the result that the upper disk 17' continues to move downwardly and thereby compresses the springs 15 25', which latter in turn exert pressure on the lower disk with the result that the lower disk holds the cover firmly in engagement with the casing. At the same time the wedge-shaped plates 32' borne by the upper 20 disk 17' engage the rounded projections 29' of the fingers 27', moving the upper ends of the latter inwardly and the rounded noses 31' thereof outwardly, with the result that each rounded nose forms an indentation 25 in the rim of the cover as depicted to the left in Fig. 6. On the idle stroke of the heading device, the springs 25' are permitted to expand, which effects movement of the disks 17' and 19' to their relative 30 extremes of movement, and consequently causes the plates 32' to move away from the projections 29', whereupon the springs 44 expand and move the upper ends of the fingers 27' outwardly, causing the noses 31' 35 of the fingers to move inwardly so as to permit said noses to pass the indentations formed thereby.

In carrying out the present invention the heading device may, obviously, be used in 40 connection with any suitable power press, the one illustrated in the drawings and above described being an example of a power press which may be employed. The band-wheel 9 has connection with a stop- 45 clutch of any construction, the latter being actuated by the foot lever 46, which, when depressed, causes the stop-clutch to lock the band-wheel 9 to the crank-shaft 8 effecting a complete revolution of the latter and 50 thereby lowers and raises the heading device.

The stop-clutch is one of the "one-revolution" type and may be like the clutch disclosed in the United States Patent No. 55 394,976, granted December 25, 1888, or any other "one-revolution" clutch.

What is claimed is:

1. A heading machine for metal packages including an upper and a lower disk, said lower disk having a series of spaced openings therein, rods carried by the lower disk and arranged to extend across said openings, screws secured to the lower disk and having their free ends engaging in depressions provided therefor in said rods to hold

the latter against movement, a finger in each opening having the rod therein extending therethrough, the lower end of each finger having a nose that projects below the under face of the lower disk, the upper end of each finger having a projection, the upper disk having openings therein to receive said upper ends of the fingers, the outer walls formed by said last named openings being inclined, wedge-shaped plates secured to said inclined walls for engagement with the projections of the fingers, and springs carried by the lower disk and disposed to engage the rear sides of the fingers, said lower disk having an inner circumferential groove. 70 75 80

2. A heading machine for metal packages including an upper and a lower disk each having a series of openings, the openings of the disks alining with each other, a finger pivoted in each of the openings of the lower disk and having outwardly extending noses, the upper ends of the fingers extending in the openings of the upper disk and each having a projection on its front face, a 85 wedge-shaped plate secured in each of the openings of the upper disk and arranged to engage said projections of the fingers, and a spring for each finger carried by the lower disk and bearing against the rear 90 faces of the fingers, said lower disk having an inner circumferential groove that is disposed to encircle the noses of the fingers. 95

3. A heading machine for metal packages including an upper and a lower disk, fingers 100 pivoted to the lower disk and having outwardly extending noses on the front faces of their lower ends and outwardly extending projections on the front faces of their upper ends, and cam means carried by the 105 upper disk to engage said projections, said lower disk having a circumferential inner groove that encircles said noses of the fingers.

4. A heading machine for metal packages 110 having casings with enlarged upper ends and covers the rims of which engage on opposite sides of the enlarged casing ends, including a lower member formed with an inner circumferential groove that receives 115 the peripheral or outer side of the cover, a series of pivoted bending elements carried by said member within the confines of the boundary thereof having their lower ends for engagement with the inner side of the 120 cover, and an upper member having means to operate said elements to move the lower ends thereof outwardly in a direction toward the groove of the lower member.

5. A heading machine for metal packages 125 having casings with enlarged upper ends and covers the rims of which engage on opposite sides of the enlarged casing ends, including a lower member formed with an inner circumferential groove that receives the 130

peripheral or outer side of the cover, a series of pivoted bending elements carried by said member within the confines of the boundary thereof having their lower ends for engagement with the inner side of the cover, an upper member, and means carried by the upper member for engagement with the upper ends of said elements on their outer faces to move the lower ends thereof in a

direction toward the groove of the lower 10 member.

In testimony whereof I hereunto affix my signature in the presence of two witnesses.

ALBERT J. MEIER.
